APPARATUS FOR PLUCKING FEATHERS

Edward J. Albright, Chicago, Ill., assignor to
E. J. Albright & Co., Chicago, Ill., a copartnership

Application April 9, 1945, Serial No. 587,262

10 Claims. (Cl. 17—11.1)

1 The invention relates to improvements in apparatus for plucking feathers from fowl and is more particularly concerned with improvements in the construction of the rotors embodied in such apparatus and operative to quickly and efficiently remove the feathers without imparting damage to the fowl.

The removal of feathers, mechanically, from fowl is advantageous particularly when performed in packing establishments handling large volumes of dressed poultry. Machines and apparatus now employed with varying degrees of success for removing the feathers from fowl include various types of mechanism specifically provided to perform the feather removing operation. Such mechanism usually consists of one or more rotary elements including means to resiliently and firmly strike and bear against various areas of a fowl so as to remove the feathers. Many such mechanisms include, as the means for directly contacting the fowl, radially extending resiliently flexible striking elements or fingers which often become broken and for this or for various other reasons require replacement.

In known types of apparatus of the character referred to, it is very difficult to effect removal and replacement as well as initial mounting of the striking elements with the result that broken or damaged striking elements are often permitted to remain in the apparatus and consequently the efficiency of the apparatus is greatly impaired. It is, therefore, an object of the present invention to provide an apparatus of the character described with novel rotors embodying novel features of construction particularly adapting the rotors for easy and quick removal and insertion of the flexible plucking fingers.

Another object of the invention is to provide a rotor of the character described of such construction as to minimize the amount of time and effort needed to mount the plucking fingers thereon firmly.

Another object of the invention is to provide a rotor which is easy to install, efficient and positive in operation and use, and not expensive to manufacture.

Another object is to provide an apparatus of the kind described with spaced rotors having fingers or beaters arranged thereon in such manner as to impart a rotary motion to a fowl as it advances between said rotors during the feather plucking operation.

Other and further objects of the present invention will be apparent from the following description and claims and are illustrated in the accom-

2 panying drawing, which by way of illustration, shows a preferred embodiment and the principle thereof and which is considered to be the best mode contemplated for applying that principle. Other embodiments of the invention embodying the same or equivalent principle may be used and structural changes may be made as desired by those skilled in the art without departing from the present invention and the purview of the appended claims.

In the drawings:

Fig. 1 is a side elevational view of a feather plucking apparatus embodying features of the present invention and showing fragments of the various coverings broken away.

Fig. 2 is a sectional detail view taken substantially on line 2—2 of Fig. 1.

Fig. 3 is an enlarged longitudinal sectional detail view of an end portion of one of the rotors.

Fig. 4 is a transverse sectional detail view of the rotor, taken on line 4—4 of Fig. 3 and omitting the fingers.

Fig. 5 is a fragmentary perspective view of a modified form of rotor.

Fig. 6 is a diagrammatic view illustrating the action of the rotors during rotation effective to impart rotary movement of the fowl therebetween.

30 The feather plucking apparatus illustrated in the accompanying drawings is of a kind adapted to have fowl carried thereto and therethrough continuously by means of an overhead conveyer 11, best illustrated in Fig. 1, of a kind adapted to advance fowl directly to said apparatus from a scalding tank, not shown. The overhead conveyer 11 may be provided with a plurality of pendants 12 suitably spaced apart longitudinally therealong, as shown, and each of which carries on its lower end a conventional frame or carrier 13 providing means for quickly and easily suspending or removing fowl therefrom. As shown, the fowl, indicated at 14 in Fig. 2, is suspended from the carriers 13 by having its feet wedgingly clamped therein.

40 The apparatus selected for illustration is of a type best suited to embody the features of the present invention, and it consists generally of a pair of frame members 15 spaced apart one on each side of the path taken by the fowl as it is advanced along the overhead conveyer. Each of the frame members 15 consists of a skeleton-like structure having upwardly extending ends 16 providing firm supports for bearings 17 which constitute journals for the end portions of a

shaft 18 when the latter is extended between said bearings.

It will be noted upon reference to Fig. 1 that frame ends 16 are of different heights to thereby dispose the bearings 17 at different elevations, and as a result, the shaft 18 is inclined longitudinally as shown. Each shaft 18 carries a pulley 19 connected by belts 21 with a pulley 22 mounted upon the shaft 23 of a motor 24 so that each shaft 18 is rotated independently of the other in an opposite direction. The motors 24 may be suitably mounted upon the respective frames 15 and to this end a plate 25, suitably slotted at 26, may be provided on each frame to enable said motors to be adjusted vertically in said frames to vary the tension on the driving belts 21.

Each of the shafts 18 is adapted to carry a rotor, generally indicated at 27, including a drum 28 and resiliently flexible fingers 29 extending radially therefrom throughout its length. When the drums are idle the fingers hang substantially limp, but when said rotors are rotated at a given rate of speed, upon operation of the motors 24, the fingers extend outwardly radially due to centrifugal force and as a result their free ends project into the area between the rotors normally occupied by the fowl as it is advanced through the apparatus by the overhead conveyer.

When the fowl is carried into position to be contacted by the fingers 29, said fingers will flex sufficiently to conform substantially to the surface configuration of the fowl and they are effective to brush or rub against such surface and thereby effectively remove all of the feathers contained within the area contacted thereby.

This beating and rubbing action of the fingers 29 frequently results in their being broken or otherwise damaged sufficiently to require their replacement. To accomplish this in an efficient and practical manner, the rotors 27 are constructed in such manner as to expedite such replacement or renewal of the fingers.

As best shown in Figs. 3 and 4, the cylindrical body or drum 28 of the rotor preferably is fashioned from tube stock having bearing portions 30 firmly secured at each end as by welding as at 31, which bearing portions are formed to receive the shaft 18 therethrough. The rotor is firmly secured to the shaft 18 for rotation in unison therewith preferably by providing a keyway 32 in said shaft for engagement by a lock screw 33 carried in the hub of the bearing 30. A plurality of circumferentially spaced angle bars 34, each of a length corresponding to the length of the drum 28, are firmly secured longitudinally along said body and extend outwardly radially therefrom.

As best shown in Fig. 4, each of the angle bars 34 is comprised of a leg or wall 35 and a flange or wall 37. The bar 34 is firmly secured to the drum 28 by welding the free edge of the leg 35 in abutment with the drum surface as at 36 to provide in effect external radial webs. The flange 37 of each angle bar is disposed substantially at right angles to the leg 35 and extends in a direction which is substantially tangent to a circle the radius of which is equal to the distance from the center of the shaft 18 to the flange 37. The flange 37 of each angle bar 34 is suitably provided with longitudinally spaced openings 38 each to receive one of the fingers 29 to thereby provide a firm, yet easily separable mounting for said fingers. Such a mounting is afforded in the present instance by providing

the base portion of each of the fingers 29 with spaced apart external circumferential flanges 39 and 41, which flanges are adapted to be disposed on either side of the flange 37 of the angle bar on which it is mounted.

In order to mount one of the fingers 29 in place, the free end thereof is thrust upwardly and outwardly through the opening 38 and the flange 39 is then forced through said opening until it is entirely disposed on the top side of said wall portion. The flange 41 on the end of the finger is, of course, sufficiently heavy to resist movement of the finger outwardly through its mounting opening 38. The finger 29 may be easily and quickly removed by forcing said finger and its flange 39 downwardly through the opening 38.

The rotors may be partially covered as by semi-cylindrical casing members 42 mounted one on each frame 15, and similarly a casing 43 may enclose each set of the drive pulleys and drive belts.

The rotor illustrated in Fig. 5 is substantially like the rotors embodied in the apparatus previously described, but in this instance the angle bars 34a are firmly attached, as by welding at 44, to the shaft 18a. This construction eliminates the need for a drum 28 and requires that the radially disposed wall or web portions 35a of the angle bars 34a be of sufficient length as to provide a rotor of the necessary diameter. As shown, the circumferentially disposed flanges 37a of each of the angle bars are disposed in a common direction and each is provided, as in the previously discussed apparatus, with a row of openings 38a, each to receive a finger 29. Rigidity is provided in the rotor by arranging tie straps 45 between adjacent angle bars 34a, which straps preferably are located at the ends of the rotor and are secured at their ends to the complementary portions of the related angle bars as by welding at 46.

It is apparent that the rotor shown in Fig. 5 is substantially like the rotor previously described in that it has a plurality of circumferentially spaced apart rows of fingers 29 which are adapted to strike against the fowl as the latter is passed between a pair of such rotors. The fingers 29 may, in the instant construction, be easily and quickly inserted in place or removed because of the relatively open construction of the rotor.

It is preferred that the fingers be arranged on the rotors of either construction in such manner that each rotor presents the appearance and embodies the characteristics of a helix so as to cause said rotors, during operation of the machine, to impart a rotary motion to the fowl passing therebetween. Such rotation of the fowl is desirable since it progressively locates various areas of the fowl in position to be acted upon by the rapidly moving fingers 29. Such positioning of the fingers and the resultant rotation of the fowl is best illustrated in Fig. 6 where it will be noted the holes 38 (or 38a) in the angle bars are alternately staggered circumferentially so that the rows of fingers carried therein are longitudinally inclined circumferentially as indicated by the broken lines 47.

It should be evident that the present invention, as disclosed herein, contemplates the provision of durable and inexpensively manufactured means for carrying a plurality of resiliently flexible fingers, so as to provide a rotor that is easy to assemble and highly efficient in operation and use, and that the invention may embody a variety of modifications in detail construction without

departing from the spirit of the invention and the scope of the appended claims.

I claim:

1. A rotor for a feather plucking apparatus comprising, in combination, a cylindrical body, external radial webs substantially co-extensive with the length of said body, flanges on the free edges of said webs, said flanges having spaced openings therein, and outwardly extending radial fingers detachably mounted one in each opening.

2. A rotor for a feather plucking apparatus comprising, in combination, a cylindrical body, external radial webs co-extensive with the length of said body, flanges on the free edges of said webs, said flanges extending in a direction substantially tangent to a circle having a radius equal to the distance from the axis of said body to said flanges, and outwardly extending radial fingers carried by said flanges.

3. A rotor for a feather plucking apparatus comprising, a shaft, circumferentially spaced radial webs on and extending a substantial portion of the length of said shaft but stopping short of its ends, flanges on the free edges of the said webs each extending in a direction which is tangential to a circle having a radius equal to the distance from the center of the shaft to the flange, said flanges having spaced openings therein, and outwardly extending radial fingers mounted one in each opening.

4. A rotor for a feather plucking apparatus comprising, a shaft, circumferentially spaced radial webs on and extending a substantial portion of the length of said shaft but stopping short of its ends, flanges on the free edges of the said webs each extending in a direction which is tangential to a circle having a radius equal to the distance from the axis of the shaft to the flange, straps extended between and secured to adjacent flanges, said flanges having spaced openings therein, and outwardly extending radial fingers mounted one in each opening.

5. A rotor for an apparatus of the kind described comprising, in combination, a shaft having bearing portions at its ends, a plurality of circumferentially spaced angle bars extending a substantial portion of the length of the shaft but stopping short of the bearing portions, each of said angle bars being attached to said shaft along an edge of one angle wall as by welding and extending radially outwardly from the body to dispose the other angle wall in a direction which is tangential to a circle having a radius equal to the distance from the axis of the shaft to the last mentioned angle wall, the said last mentioned angle walls all extending in a common direction, and means anchoring adjacent angle bars one to the other.

6. A rotor for an apparatus of the kind described comprising, in combination, a shaft having bearing portions at its ends, a plurality of circumferentially spaced angle bars extending a substantial portion of the length of the shaft but stopping short of the bearing portions, each of said angle bars being attached to said shaft along an edge of one angle wall so as to dispose its other angle wall in a direction which is tangential to a circle having a radius equal to the distance from the axis of the shaft to the last mentioned angle wall, the last mentioned angle walls all extending in a common direction, and straps connecting adjacent angle bars one to the other at their ends.

7. A rotor for an apparatus of the kind described comprising in combination, a shaft having

bearing portions at its ends, a plurality of circumferentially spaced angle bars extending a substantial portion of the length of the shaft but stopping short of the bearing portions, each of said angle bars being attached to said shaft along an edge of one angle wall as by welding and extending radially outward from the body to dispose the other angle wall in a direction which is substantially tangential to a circle having a radius equal to the distance from the axis of the shaft to the last mentioned angle wall, said last mentioned angle walls all extending in a common direction and having outwardly extending radial fingers mounted thereon, and means anchoring adjacent angle bars one to the other.

10. A rotor for an apparatus of the kind described comprising in combination, a shaft having bearing portions at its ends, a plurality of circumferentially spaced angle bars extending a substantial portion of the length of the shaft but stopping short of the bearing portions, each of said angle bars being attached to said shaft along an edge of one angle wall so as to dispose its other angle wall in a direction which is substantially tangential to a circle having a radius equal to the distance from the axis of the shaft to the last mentioned angle wall, the last mentioned angle walls all extending in a common direction and having outwardly extending radial fingers mounted thereon, and straps connecting adjacent angle bars one to the other at their ends.

15. A rotor for feather plucking apparatus comprising, in combination, a rotatable elongated body, spaced external radial webs carried on the periphery of said body and extending a substantial portion of the length thereof, flanges on the free edges of said webs, said flanges having spaced openings therein, and outwardly extending radial fingers detachably mounted one in each opening.

20. A rotor for feather plucking apparatus comprising a rotatable elongated body, spaced radial webs mounted on the periphery of said body and extending a substantial portion of the length thereof, flanges on the free edges of said webs, each extending in a direction which is tangential to a circle having a radius equal to the distance from the axis of the body to the flange, said flanges having spaced openings therein and outwardly extending radial fingers mounted one in each opening.
